DESIGN FOR A BADGE OR SIMILAR ARTICLE

William Edward Stanbury, Kansas City, Mo.

Application January 7, 1939, Serial No. 82,220

Term of patent 14 years

To all whom it may concern:

Be it known that I, William Edward Stanbury, residing at Kansas City, in the county of Jackson and State of Missouri, have invented a new, original, and ornamental Design for a Badge or Similar Article, of which the following is a specification, reference being had to the accompanying drawing, forming part thereof, in which,

Fig. 1 is a front elevation of a badge showing my new design.

Fig. 2 is a side elevation of the badge shown in Fig. 1.

I claim:

The ornamental design for a badge or similar article, substantially as shown.

WILLIAM EDWARD STANBURY.
